FIG. 4

ACOUSTIC AMPLIFIER

BACKGROUND OF THE INVENTION

1. Field of the Invention

The present invention relates to acoustic amplifiers, and more particularly, to an acoustic amplifier which is so constructed as to prevent pop noise from arising at the closure of the power source switch.

2. Description of the Prior Art

In the field of acoustic amplifiers, so-called pop noise generated when a power source is turned on has become a problem. Pop noise is generated by a cause as will be hereinafter described and is offensive to the ear. Moreover, an excessive current flows through a speaker as the load of the amplifier at the closure of the power source switch, and it is feared that the speaker may be damaged by the impulse of the excessive current.

SUMMARY OF THE INVENTION

Accordingly, a principal object of the present invention is to provide an acoustic amplifier which is free from pop noise arising at closure of a power source switch.

Another object of the present invention is to provide an acoustic amplifier which is provided with pop noise-preventing means being so constructed as to be independent of an amplifier circuit under steady state conditions.

Still another object of the present invention is to provide an acoustic amplifier for which it is not necessary to add a capacitor for the purpose of preventing pop noise.

The present invention itself and the other objects of the present invention will become apparent from the following description taken in conjunction with the accompanying drawings.

BRIEF DESCRIPTION OF THE DRAWINGS

FIG. 1 is a circuit diagram showing an embodiment of an acoustic amplifier according to the present invention;

FIG. 2a to 2d are characteristic diagrams for the acoustic amplifier circuit in FIG. 1, among which FIGS. 2a and 2b show changes-versus-time of a mid-point potential V_a of a push-pull output amplifier circuit and a transient current flowing through an output terminal OUT in the case of the absence of a starting switch ST, respectively, while FIGS. 2c and 2d show changes-versus-time of the base potentials (V_b) Q_1 and (V_b) Q_2 of a pair of input transistors of a differential amplifier and the mid-point potential V_a in the case of the presence of the starting switch ST, respectively; and

FIGS. 3 and 4 are circuit diagrams each showing another embodiment of the present invention.

PREFERRED EMBODIMENTS OF THE INVENTION

FIG. 1 shows an embodiment of an acoustic amplifier according to the present invention.

Illustrated as an example of the acoustic amplifier in the figure is a power amplifier circuit. Referring to the figure, transistors Q_1 to Q_3 constitute a part of a differential amplifier. The transistor Q_3 functions as a constant-current source. The base electrodes of the transistors Q_1 and Q_2 are respectively applied with a low-frequency input signal and a feedback signal. C_1 designates a capacitor, for coupling inputs, which is connected between an input terminal IN and the base electrode of the transistor Q_1 . A capacitor C_2 is employed in order to attenuate the AC component of a supply voltage (namely, as a ripple filter).

Transistors Q_4 and Q_5 constitute the principal part of a level shift circuit, and function so as to lower the DC level of the output voltage of the differential amplifier.

Transistors Q_6 and Q_7 constitute a driver circuit which drives a push-pull circuit at the succeeding stage.

Transistors Q_8 to Q_{11} form a B-class push-pull amplifier circuit. Transistors Q_8 and Q_9 and transistors Q_{10} and Q_{11} are connected in Darlington configuration, respectively. As a result, transistors Q_8 and Q_9 form an equivalent PNP transistor, while transistors Q_{10} and Q_{11} form an equivalent NPN transistor. The output voltage V_a of the amplifier circuit is supplied through a capacitor C_6 to an output terminal OUT, and is also fed back through resistors R_8 and R_{12} and a capacitor C_3 to the differential amplifier at the preceding stage.

The feedback circuit is used in order to effect temperature compensation for the amplifier, and to make the distortion factor small.

C_4 indicates a capacitor for providing phase shift correction while C_7 represents a capacitor for preventing oscillations. A capacitor C_5 is employed for bootstrap.

In such a power amplifier circuit, a starting switch circuit ST employing a non-linear element composed of transistors Q_{12} and Q_{13} and resistors R_{13} and R_{14} is provided in accordance with the present invention in order to prevent the occurrence of pop noise.

The base electrodes of the transistors Q_{12} and Q_{13} are connected to the juncture between resistors R_2 and R_3 , while the emitter electrodes are connected through the resistor R_{14} to a voltage source V_{cc} . The resistor R_{13} is connected between the emitter electrodes of the transistors Q_{12} and Q_{13} and a ground terminal. The emitter electrodes of the transistors Q_{12} and Q_{13} , accordingly, have applied thereto a voltage which is produced by dividing the supply voltage V_{cc} by the resistors R_{13} and R_{14} . The collector electrode of the transistor Q_{12} is connected to the capacitor C_3 , while the collector electrode of the transistor Q_{13} is connected to the input electrode of the transistor Q_6 of the driver circuit.

Before explaining the operation of the acoustic amplifier according to the present invention, the process in which pop noise is generated will be described in connection with the power amplifier circuit without the starting means ST.

In the absence of the starting means ST:

1. At the moment at which a power switch SW is turned on, the terminal voltage of the capacitor C_2 is 0 V, and hence, the transistors Q_1 and Q_2 are non-conductive. In consequence, the transistors Q_4 and Q_6 to Q_9 are also non-conductive. Since the time constant of resistor R_{10} and the capacitor C_5 is small, the output potential V_a of the push-pull circuit (the mid-point potential) instantly rises from its original state (the electric potential of the circuit before the closure of the power switch SW) to potential of the supply voltage V_{cc} . 2. When the mid-point potential V_a becomes equal to the supply voltage V_{cc} , the capacitor C_3 is charged through the resistor R_8 . The base potential of the transistor Q_2 is thereby made higher than that of the transistor Q_1 , so that the transistor Q_2 is rendered conductive. As a result, the transistors Q_4 and Q_6 to Q_9 are rendered conductive, and the mid-point potential V_a becomes

substantially equal to ground potential (the original potential).

3. When the mid-point potential V_q becomes equal to ground potential, charges stored in the capacitor C_3 are discharged through the resistor R_8 . The base potential of the transistor Q_2 becomes lower than that of the transistor Q_1 and the mid-point potential V_q suddenly increases to the supply voltage V_{cc} again.

4. Subsequently, the capacitor C_3 is charged again. Finally, the base potentials of the transistors Q_1 and Q_2 reach an equilibrium point and the mid-point potential V_q is set at a predetermined value (for example, $\frac{1}{2}V_{cc}$).

In this manner, in the absence of the starting means ST, the mid-point potential V_q travels or changes between the ground potential and the supply voltage as is illustrated in FIG. 2a. To the load terminal OUT, there flows a transient current which is as shown in FIG. 2b and which results from a differentiation of the mid-point voltage V_q by the coupling capacitor C_6 . Pop noise is generated at this time.

The embodiment in FIG. 1 employs the starting switch circuit ST which, in order to prevent a large transient current from flowing to the load at the moment of the closure of the power source switch, operates so as to first set the mid-point potential V_q at approximately ground potential at the instant of the connection of the power supply, and to thereafter raise the mid-point potential V_q gradually from the ground potential to, for example, the potential of a half of the supply voltage V_{cc} . When the mid-point potential V_q becomes equal to $\frac{1}{2}V_{cc}$, the starting switch circuit ST becomes independent of a signal path for low-frequency signals. Description will now be made of the operation.

In the presence of the starting means ST:

1. At the moment at which the power switch SW is turned on, the terminal voltage of the capacitor C_2 is 0 V, so that the base potentials of the transistors Q_{12} and Q_{13} become 0 V. Simultaneously therewith, the base-emitter junctions of the transistors Q_{12} and Q_{13} are biased in the forward direction, to render the transistors conductive. Upon the conduction of the transistor Q_{13} , the transistors Q_6 and Q_7 are also rendered conductive (saturated). The mid-point potential V_q is first set, as illustrated in FIG. 2d, at 0 V (strictly, at $2V_{be\text{sat}}$ where $V_{be\text{sat}}$ denotes the base-emitter voltage drop in the saturation region).

2. Since the transistor Q_{12} is conductive, the capacitor C_3 is charged through the transistor Q_{12} , and the capacitor C_2 is also gradually charged through resistor R_1 . As the capacitor C_2 is gradually charged, the base potentials of the transistors Q_{12} and Q_{13} become higher. Eventually, the transistors Q_{12} and Q_{13} are reverse-biased and rendered non-conductive at a time t_1 .

The transistor Q_2 is rendered conductive (saturated) at this time, since the capacitor C_3 is charged by previously rendering the transistor Q_{12} conductive so that, as illustrated in FIG. 2c, the base potential $(V_b)_{Q_2}$ of the transistor Q_2 may become higher than the base potential $(V_b)_{Q_1}$ of the transistor Q_1 . Upon the conduction of the transistor Q_2 , the transistor Q_4 is rendered conductive, and accordingly, the transistors Q_6 and Q_7 continue to operate in the saturation region.

3. Subsequently, since the mid-point potential V_q is substantially 0 V, the charges stored in the capacitor C_3 are discharged through the path of feedback resistor R_8 , the transistor Q_9 , ground, and resistor R_{12} and the

base potential $(V_b)_{Q_2}$ begins to decrease. On the other hand, the base potential $(V_b)_{Q_1}$ continues to rise, and the difference between both the base potentials becomes small. In due course, the differential amplifier begins to operate in a linear region (dynamic range) in its transmission characteristic at a time t_2 . As shown in FIG. 2d, the mid-point potential V_q rises gradually.

Upon an increase in the mid-point potential V_q , the discharge action of the capacitor C_3 becomes slow. When the mid-point potential V_q exceeds the base potential $(V_b)_{Q_2}$, the capacitor C_3 begins charging again. With the charging, the base potentials $(V_b)_{Q_1}$ and $(V_b)_{Q_2}$ rise substantially in balance. Finally, the differential amplifier is balanced, and the mid-point potential V_q is fixed at $\frac{1}{2}V_{cc}$ (at no signal).

It is required that, when the transistor Q_{13} falls into the cut-off region, the base potential $(V_b)_{Q_2}$ be higher than the base potential $(V_b)_{Q_1}$. To this end, it is necessary that the time constant involved in the charging of the capacitor C_2 be made larger than the time constant involved in the charging of the capacitor C_3 . Although various elements are concerned with the time constants, such requirement is fulfilled by, for example, making the resistance of the resistor R_1 in the bias circuit and the capacitance of the capacitor C_2 sufficiently large for attenuating ripples. Even if the constants of the bias circuit are altered in this manner, the characteristics of the low-frequency amplifier are not influenced.

As described above, in accordance with the present embodiment, the mid-point potential V_q is first set at ground potential and then it gradually increases from this voltage to $\frac{1}{2}V_{cc}$, as illustrated in FIG. 2d. Therefore, no large current flows through the load. The pop noise can, accordingly, be prevented.

In the steady state reached at a short time after the closure of the power supply switch, the transistors Q_{12} and Q_{13} automatically fall into the cut-off region. The time constant circuit (C_2 , R_1 , etc.) of the starting switch ST is thereby isolated from the path of low-frequency signals at, for example, the base electrodes of the transistors Q_2 and Q_6 . It is, therefore, unnecessary to consider the capacitor C_2 , the resistor R_1 , etc. among the design conditions of the signal path of the amplifier on account of the starting switch ST and the time constant circuit thereof. Accordingly, the circuit design is subject to no restriction. The low-frequency signals are not influenced by the capacitor C_2 , resistor R_1 etc., so that the design of the signal paths can be made with these elements neglected. The design of electrical characteristics such as low frequency characteristics is, therefore, facilitated.

These advantageous features are accomplished by the operation of the starting means ST that it functions only during the period of transition after the closure of the power source, and that it is independent of the amplifier circuit under steady state conditions.

Where the non-linear elements of the transistors Q_{12} and Q_{13} are rendered conductive at the transition and non-conductive under steady state conditions, the capacitors C_2 and C_3 intrinsically required in the amplifier circuit are utilized for the time constant circuit of the starter circuit and in the present embodiment. It is thus unnecessary to add new capacitors. (It has been a recent tendency that the linear circuit of the acoustic amplifier, etc. is put into the form of an integrated semiconductor circuit, similarly to the digital circuit. From

the viewpoint of an occupied area, however, it is difficult to make a capacitor of large capacity in a monolithic semiconductor substrate. It is, therefore, necessary to mount capacitors in the individual form outside the substrate. Accordingly, an increase in the number of capacitors increases not only the number of components, but also the number of external terminals of the integrated semiconductor circuit. Also, it leads to an increase in the number of operations at assembly.)

It is, accordingly, very effective that, as in the present embodiment, the capacitors, being originally necessary, can be utilized as they are.

As a further advantage of the present embodiment, the following can be mentioned.

The period ($t_2 - t_0$) during which the mid-point potential V_q is held substantially at 0 V can be made long by making large the time constant based on the capacitor C_2 and the resistor R_1 , etc. The signal of a small signal-amplifier circuit to be connected at the stage preceding the power amplifier circuit, can thus be prevented from flowing to the speaker of the load during that period.

More specifically, even if a signal causing the pop noise is generated in the small signal-amplifier circuit, the pop noise will not occur in the speaker since the power amplifier circuit does not operate during the period from the time t_0 to the time t_2 . The necessity for providing separate, pop noise-preventing means for the small signal-amplifier circuit is, therefore, eliminated.

FIG. 3 shows another embodiment of the acoustic amplifier according to the present invention. The fundamental construction of the amplifier circuit except the starting switch ST is similar to the embodiment in FIG. 1.

Referring to FIG. 3, a diode D_{23} is connected between a capacitor C_{22} for a ripple filter and a capacitor C_{22} for DC feedback.

The cathode electrode of a diode D_{24} is connected to the base electrode of a transistor Q_{29} of an A-class driver circuit, while the anode electrode is connected to the collector electrode of a transistor Q_{21} .

The grounded emitter type transistor Q_{21} has the base electrode grounded through resistors R_{23} and R_{22} , and has the collector electrode connected to a voltage source V_{cc} through a resistor R_{26} and diodes D_{21} and D_{22} .

The operation of the acoustic amplifier provided with such starter switch ST will now be explained.

1. At the moment at which the power supply switch is turned on, the terminal voltage of the capacitor C_{22} is 0 V, and hence, the transistor Q_{21} is non-conductive. Via the diodes D_{21} , D_{22} and D_{24} and the resistor R_{26} , base currents flow in the transistor Q_{29} and the transistor Q_{30} , to render the transistors Q_{29} and Q_{30} conductive. The mid-point potential V_q is set at approximately 0 V.

Simultaneously therewith, the base potential of a transistor Q_{27} is held at approximately 0 V, since the resistance of a resistor R_{28} is sufficiently smaller than that of a resistor R_{30} . The diode D_{23} is consequently forward-biased, and rendered conductive.

2. As the capacitor C_{22} is gradually charged, the base potential of the transistor Q_{21} increases. Therefore, the transistor Q_{21} is rendered conductive (saturated). The collector potential of the transistor Q_{21} , namely, the anode potential of the diode D_{24} , becomes substantially ground potential and diode D_{24} is rendered non-conductive.

At this time, the base potential of the transistor Q_{27} has become higher than that of a transistor Q_{24} , since the capacitor C_{23} has been charged by the previous conduction of the diode D_{23} . As has been explained in connection with the embodiment in FIG. 1, the mid-point potential V_q continues to be substantially 0 V.

3. Thereafter, as in the embodiment in FIG. 1, the difference between the base potentials of the transistors Q_{24} and Q_{27} gradually decreases. As a result, the mid-point potential V_q begins to gradually rise from approximately 0 V to $\frac{1}{2} V_{cc}$. Finally, the differential amplifier is brought into the equilibrium, to set the mid-point potential V_q at $\frac{1}{2} V_{cc}$.

Under steady state conditions, the differential amplifier is balanced, and the base potentials of its transistors Q_{24} and Q_{27} are substantially equal. Therefore, the diode D_{23} is reverse-biased by an amount corresponding to the voltage drop of a resistor R_{21} , and is held non-conductive.

20 In some differential amplifiers, the diode D_{23} is somewhat forward-biased under steady state conditions. In this case, no inconvenience occurs unless the threshold voltage of the diode (about 0.7 V for a silicon diode) is exceeded.

25 FIG. 4 shows still another embodiment of the acoustic amplifier according to the present invention.

Referring to the FIG., the starter switch ST is composed of resistors R_{51} and R_{52} and a transistor Q_{49} .

The resistors R_{51} and R_{52} are connected in series between a voltage source V_{cc} and a ground terminal. The transistor Q_{49} has its base electrode connected through the resistor R_{51} to the voltage source V_{cc} , has its collector electrode connected to the base electrode of a transistor Q_{43} for level shift purposes, and has its emitter electrode connected to a capacitor C_{43} for DC feedback.

Description will now be made of the operation of the acoustic amplifier provided with such a starting switch circuit ST.

40 1. At the moment at which power switch SW is turned on, the base potential of a transistor Q_{42} becomes approximately 0 V, to bias the transistor Q_{49} in the forward direction and to render it conductive, because the resistance of a resistor R_{50} is small as compared with that of a resistor R_{47} . Upon the conduction of the transistor Q_{49} , a base current flows in the transistor Q_{43} , and the transistor Q_{43} is rendered conductive. Simultaneously therewith, transistor Q_{44} is rendered conductive (saturated). The mid-point potential V_q is set at substantially 0 V.

45 2. Thereafter, the transistor Q_{49} becomes non-conductive, if the resistances of the resistors R_{51} and R_{52} are selected so as to satisfy the following condition:

55

$$\frac{R_{42}}{R_{41} + R_{42}} > \frac{R_{52}}{R_{51} + R_{52}} - \frac{V_{be}}{V_{cc}}$$

60 where V_{be} denotes the threshold voltage of the transistor, and the voltage drop of a resistor R_{43} is neglected.

At this time, the base potential of the transistor Q_{42} is made higher than the base potential of a transistor Q_{41} in such a way that the transistor Q_{49} is previously rendered conductive, to thereby charge the capacitor C_{43} . The mid-point potential V_q , therefore, continues to be substantially 0 V.

The subsequent operation is substantially the same as in the circuit in FIG. 1.

The present invention can eliminate pop noise by providing the starter switch ST circuit, not only in a power amplifier circuit, but also in a small signal-amplifier circuit or the like acoustic amplifier which is connected at the preceding stage of the power amplifier circuit.

Although, in the foregoing embodiments of the power amplifier circuits, the amplifier circuit at the preceding stage part has been described as being a differential amplifier circuit, it is needless to say that the present invention is similarly applicable to a power amplifier circuit in which a single stage of a class A amplifier circuit is arranged at the preceding stage.

The transistor Q_{21} of the starting switch circuit in the acoustic amplifier in FIG. 3 is held conductive under steady state conditions, and current always flows therethrough. In contrast, the corresponding transistors in the embodiments in FIGS. 1 and 4 are held non-conductive under the steady state, so that the embodiments are effective in this respect.

In any of the foregoing embodiments, the ripple filter employed in the amplifier circuit is also used for the circuit which raises the output potential of the output amplifier circuit from the original potential to the steady state potential, whereby a reduction in the number of elements used is achieved. A separate time constant circuit, however, may also be connected at the input part of the starting switch circuit. In this case, the principal objects of the present invention, in that pop noise is eliminated and pop noise-preventing means is independent of the point at which the amplifier circuit is controlled by the switch circuit, under steady state conditions, can be achieved.

We claim:

1. An acoustic amplifier comprising:
a first amplifier circuit;
a second amplifier circuit having an input coupled to an output of said first amplifier circuit;
a power source terminal to which a source of power for said amplifier circuits is applied;
a power switch, one terminal of which is connected to said power source terminal;
a feedback means connected between an output of said second amplifier circuit and an input of said first amplifier circuit;
a capacitor connected between said input of said first amplifier circuit and ground potential;
first means, having a first terminal connected to another terminal of said power switch and a second terminal connected to said input of said second amplifier circuit, respectively, for setting the potential of the output of said second amplifier circuit at ground potential during a certain period of time starting from the instant of time when said power switch is closed; and

second means, having a first terminal connected to said another terminal of the power switch and a second terminal connected to said capacitor, respectively, for supplying a charging current to said capacitor during said period of time.

2. An acoustic amplifier according to claim 1, wherein said first amplifier circuit comprises a differential amplifier circuit.

3. An acoustic amplifier according to claim 2, further including voltage divider circuits and wherein said first and second means are comprised of a transistor circuit having a reference potential input, a control input and a pair of outputs, said reference potential input and said control input being connected between said voltage divider circuits, said voltage divider circuits supplying a voltage produced by dividing a supply voltage to each of said inputs, and said power switch, and said pair of outputs being connected to an input of said differential amplifier circuit and the input of said second amplifier circuit, respectively.

4. An acoustic amplifier according to claim 2, further including a voltage divider circuit, and wherein said first and second means are comprised of a transistor circuit having a reference potential input, a control input and an output, said reference potential input being connected to one side of said differential amplifier circuit, said control input being connected between said voltage divider circuit, said voltage divider circuit supplying a voltage produced by dividing a supply voltage to said control input, and said power switch and the output being connected to an input of said differential amplifier circuit.

5. An acoustic amplifier according to claim 2, wherein said second means comprises a first diode connected between a first reference point on a voltage divider circuit directly connected to said power switch and an input of said differential amplifier circuit, and said first means comprises a transistor circuit including a transistor and a diode connected thereto, coupled between a second reference point on said voltage divider circuit and the input of said second amplifier circuit.

6. An acoustic amplifier according to claim 2, wherein said second amplifier circuit comprises a push-pull amplifier circuit.

7. An acoustic amplifier according to claim 6, wherein said second amplifier circuit further includes a driver circuit connected to said push-pull amplifier circuit, and further comprising a level shift circuit coupling the output of said differential amplifier circuit to said driver circuit.

8. An acoustic amplifier according to claim 6, further including a ripple filter circuit connected to said power switch, and wherein said feedback path comprises a resistor-capacitor network connected between the output of said push-pull amplifier circuit and an input of said differential amplifier circuit.
